(57) **CLAIM**

An ornamental design for a refill holder for candle dispenser, as shown and described.

DESCRIPTION

FIG. 1 is an upper frontal perspective view of the design; FIG. 2 is a top plan view thereof;

FIG. 3 is a front elevational view thereof;

FIG. 4 is a left side elevational view thereof;

FIG. 5 is a rear elevational view thereof;

FIG. 6 is a right side elevational view thereof; and,

FIG. 7 is a bottom plan view thereof.

The broken lines in FIGS. 1-7 are for the purpose of illustrating environmental structure and form no part of the claimed design.

In a preferred embodiment the holder is useful in connection with dispensing an air treatment chemical, such as an insect repellent, if a substrate part of the holder is heated over a candle.
